UNITED STATES PATENT OFFICE

119,337

DESIGN FOR A MODEL AIRPLANE

Benson Russell Shaw, Washington, D. C., assignor
to Washington Institute of Technology, Inc.,
Washington, D. C., a corporation of Delaware

Application May 12, 1939, Serial No. 84,954

Term of patent 3½ years

To all whom it may concern:

Be it known that I, Benson Russell Shaw, a citizen of the United States, residing at Washington, District of Columbia, have invented a new, original, and ornamental Design for a Model Airplane, of which the following is a specification, reference being had to the accompanying drawing, forming part thereof:

Fig. 1 is a perspective view of the model airplane showing my new design, and

Fig. 2 is a side elevation, slightly turned, of the model airplane.

I claim:

The ornamental design for a model airplane, as shown.

BENSON RUSSELL SHAW.
